UNITED STATES PATENT OFFICE

173,287

PORTABLE FAMILY SHRINE

Leo R. Slaton, Chicago, Ill.

Application March 4, 1954, Serial No. 29,318

Term of patent 14 years

(Cl. D29—23)

To all whom it may concern:

Be it known that I, Leo R. Slaton, a citizen of the United States, residing at Chicago, in the county of Cook and State of Illinois, have invented a new, original, and ornamental Design for a Portable Family Shrine, of which the following is a specification, reference being had to the accompanying drawings, forming a part hereof.

Fig. 1 is a perspective view of a portable family shrine embodying my new design, with the doors closed and

Fig. 2 is a similar view with the doors partly open.

The shrine shown in the drawings is symmetrical about its central vertical axis, the sides not seen in the drawing being similar to the sides which are shown.

I claim:

The ornamental design for portable family shrine, as shown and described.
